UNITED STATES PATENT OFFICE.

JOBBY BELPEDIO, OF BRIDGEPORT, CONNECTICUT.

REPRODUCER.

1,399,922.

Specification of Letters Patent. Patented Dec. 13, 1921.

Application filed April 20, 1920. Serial No. 375,304.

To all whom it may concern:

Be it known that I, JOBBY BELPEDIO, a citizen of the United States, residing at Bridgeport, in the county of Fairfield and 5 State of Connecticut, have invented certain new and useful Improvements in Reproducers; and I do hereby declare the following to be a full, clear, and exact description of the invention, such as will enable others 10 skilled in the art to which it appertains to make and use the same.

This invention relates to new and useful improvements in reproducers for talking machines and has for a primary object the 15 provision of a device of the above stated character, which is capable of reproducing sounds on different records now on the market and known by the following names, Columbia, Victor, Pathé and Edison, thereby 20 providing a device for universal use and one that will successfully operate on different kinds of talking machines that employ tone arms.

Another object of this invention is the 25 provision of a sound box having the usual diaphragm to which different stylus holders are connected and which have the desired type of styli for reproducing the kinds of records mentioned.

30 A further object of this invention is the provision of means for connecting the sound box to the tone arm and which will permit adjustment of said sound box to different angles, or positions for playing the different 35 types of records.

A further object of this invention is the provision of means whereby the sound box may be easily and quickly disassembled when desiring to make repairs or adjustments to 40 the diaphragm or the means that connects the same to the stylus holder.

A still further object of this invention is the provision of a reproducer of the above 45 stated character, which shall be simple, durable and efficient, and which may be manufactured and sold at a comparatively low cost.

With these and other objects in view as 50 will become more apparent as the description proceeds, the invention consists in certain novel features of construction, combination, and arrangement of parts as will be hereinafter more fully described and claimed.

55 For a complete understanding of my invention, reference is to be had to the follow-

ing described and accompanying drawings, in which:—

Figure 1 is a side elevation illustrating a reproducer constructed in accordance with 60 my invention and showing the same positioned to play a Victor or Columbia record.

Fig. 2 is a similar view, illustrating the reproducer positioned to play a Pathé record,

Fig. 3 is a similar view partly in section illustrating the reproducer positioned to play an Edison record.

Fig. 4 is a sectional view illustrating the same,

Fig. 5 is a detail sectional view taken on the line 5—5 of Fig. 3,

Fig. 6 is a fragmentary sectional view illustrating a modified form of means of connecting the diaphragm to the stylus 75 holders.

Referring in detail to the drawing, the numeral 1 indicates as an entirety a reproducer capable of playing or reproducing the sounds from different types of records now 80 on the market and includes a body 2 that has an annular side wall 3 closed at one end by a circular wall 4. The wall 4 is provided with a central sound opening 5 surrounded by a collar or flange 6 detachably secured to 85 the outer face of the wall 4 by fasteners 7. A substantially L-shaped tone arm connecting tube 8 has one of its arm portions rotatably mounted within the collar or flange 6 and has formed upon its ends an annular 90 flange 9 that fits within an annular groove 10 formed in said flange or collar 6, thus, it will be seen that the tube 8 is rotatably secured to the body 2 of the reproducer 1. The last named arm portion of the tube 8 95 is cut away to form a shoulder 11 that rests upon the face of the collar or flange 6 and co-operates with the flange 9 in securing the tube to the body or sound box 2. The outer face of the collar or flange 6 is provided with spaced sockets 12 to be engaged by a spring pressed ball 13 carried in an offset portion 14 formed on the tube 8 for holding

the tube against accidental movement or rotation in relation to the sound box or body 105 2 and the sockets 12 are so arranged to properly hold the sound box or body 2 in position for playing the different types of records.

The other arm portion of the tube 8 is 110 reduced to form a neck 15 which is received by a tone arm 16 and has frictional contact

- therewith so as to obviate the danger of the tube becoming accidentally detached from the tone arm and further said tone arm is provided with a locking sleeve 17 whereby the frictional contact between said tone arm and tube can be increased to such an extent that the tube 8 cannot be detached from the tone arm until the locking sleeve 17 has been unthreaded or released.
- 10 A disk 18 constructed from felt or any other material suitable for the purpose is placed within the body or sound box 2 and against the wall 4 and is provided with an opening in alignment with the sound opening 5 and has positioned thereon an annular cushion member 19 constructed from rubber or any other suitable material to support a diaphragm 20. An annular packing member or ring 21 is positioned against the diaphragm 20 and held against the same by an annular attaching member or ring 22 which is threaded into the body or sound box 2, thus it will be seen that the packing and diaphragm can be easily and quickly removed from the body or sound box 2 for repairs and also can be adjusted therein by the attaching ring or member 22 owing to its threaded engagement with the annular wall 3 of the sound box or body 2.
- 15 20 25 30 35 40 45 50 55 60 An attaching member 23 includes right angled flanges that engage the circular wall 3 of the sound box or body 2 and secures thereto a sheet of catgut or similar material 24 for closing the sound box to retain the sound therein. The attaching member 23 is secured to the sound box or body 2 by means of a series of fastening elements 25 that have one of their ends bent to overlie the attaching member 23 and the other end screw threaded and extending through lugs 26 formed on the wall 3 and provided with countersunk openings to receive nuts 27 threaded to said fastening elements 25.
- Spaced ears 28 are formed on the wall 3 of the body or sound box adjacent one edge of said wall 3 and have pivoted therebetween a double stylus holder 29 by set screws 30 which are provided with lock nuts 31. The stylus holder 29 is capable of adjustment with relation to the sound box or body 2 by the set screws 30 and after being adjusted the set screws 30 are turned against the stylus holder with sufficient tension to hold said stylus holder against accidental movement in relation to the sound box or body 2 and said set screws can be locked in any desired position by the lock nuts 31 threaded thereon and turned against the ears 28. The double stylus holder 29 includes a body 30 with stylus receiving portions 31 and 32 respectively. The portion 31 is in a plane with the body 30 and is provided with a stylus receiving socket 33 to receive the ordinary stylus 34 used for playing Colum-
- bia or Victor records and which is held within the portion 31 by a set screw 35. The portion 32 is disposed on an incline in relation to the body 30 and the portion 31 and carries the usual stylus 36 for playing Pathe records. The portions 31 and 32 have formed thereon trips or cams 37 to engage a trip mechanism of a talking machine forming the subject matter of a co-pending application.
- The inner ends of the styli 34 and 36 terminate adjacent each other and the body 30 has formed thereon and at a point adjacent the inner ends of said styli, a stylus arm or bar 38 which is curved and extends through an opening 39 in the wall 3 of the body or sound box and has formed on its inner end a head 40 which engages the diaphragm 20 and is provided with a screw threaded extension 41 that passes through the diaphragm and has threaded thereon a securing element 42 which also bears against the diaphragm and cooperates with the head 40 in firmly securing the stylus arm or bar 38 to the diaphragm so that the motion of the stylus holder 29 will efficiently effect the diaphragm to produce the desired sound. When the stylus 34 is used to play Columbia or Victor records, the sound box 2 is positioned as illustrated in Fig. 1 and when the stylus 36 is used to play Pathe records, the sound box is positioned as illustrated in Fig. 2.
- A stylus supporting member 43 of substantially V-shape is formed integrally with the clamping member 23 and is disposed over the catgut 24 and has spaced ears 44 formed on its apex between which is pivoted a stylus holder 45 which is of substantially S-shape, having one end connected to the diaphragm head 40 by a thread or similar element 46 that extends through an opening in the catgut 24 while the other end of said stylus holder 45 projects between and beyond the arm portions of the stylus supporting member 43 and carries an ordinary stylus 47 used to reproduce Edison records. The stylus holder 45 has formed thereon an ear 48 which is engaged by a leaf spring 49, that is secured to or formed on the clamping member 23 so that said stylus holder is capable of having pivotal movement on the supporting member 43 and at all times the thread or element 46 is kept under tension. When the stylus 47 is employed to play Edison records, the sound box 2 is positioned as illustrated in Figs. 3, 4, and 5 or horizontally over said records.
- Referring to Fig. 6 which illustrates a modified form of my invention, the stylus arm or bar 38 terminates after entering the opening 39 and has connected thereto a thread or similar element 50 which is in

turn connected to a diaphragm head 51 secured to the diaphragm. The thread or element 46 may also be connected to the head 51 as clearly shown in Fig. 6.

5 While I have shown and described the preferred embodiment of my invention, it will be understood that minor changes in construction, combination, and arrangement of parts may be made without departing 10 from the spirit and scope of the invention as claimed.

Having thus described my invention, what I claim is:—

1. A reproducer comprising an annular body having one end partly closed by a wall, a diaphragm in said body, a stylus holder carried by the body and connected to the diaphragm, a clamping ring on said body, a closure element closing said body and held 20 on the latter by said ring, apertured lugs on said body, rods extending through the lugs and having angular ends engaging the ring, and fastening means on said rods.

2. A sound box having a single diaphragm, a stylus holder pivoted to and extending radially from said sound box, a second stylus holder pivoted to and extending longitudinally from said sound box, means connecting both of said holders to

said diaphragm, and a spring engaging one 30 of said holders.

3. A reproducer comprising a circular body, a single diaphragm in said body, a double stylus holder secured to one side of the body, a support secured to the body diametrically opposite to the stylus holder and projecting over the diaphragm, a single stylus holder pivoted to said support, and means connecting the stylus holders to the diaphragm.

4. A reproducer comprising a body, a diaphragm in said body, a V-shaped support having its arms secured to one edge of said body and its apex arranged over the diaphragm, an S-shaped stylus holder pivoted 45 to the apex of said support and having one of its ends connected to the diaphragm, a projection on said holder, and a tension member secured to the body between the arms of the support and engaging the 50 projection.

In testimony whereof I affix my signature in presence of two witnesses.

JOBBY BELPEDIO.
